UNITED STATES PATENT OFFICE

RAYMOND W. DULL, OF CHICAGO, ILLINOIS, ASSIGNOR TO LINK-BELT COMPANY, OF CHICAGO, ILLINOIS, A CORPORATION OF ILLINOIS

AUTOMATIC BUCKET LOADER

Application filed September 9, 1929. Serial No. 391,137.

This invention relates to a bucket loader and particularly to the control of the bucket or its loading mechanism used in connection with a skip hoist installation. The invention generally relates to means for either automatically or manually loading buckets or containers with material either by weight or by volume, in connection with means for either automatically or manually starting the bucket up empty, partially loaded or fully loaded. Some of the principal methods of operation are as follows:

The container can be operated automatically on a predetermined time cycle or manually, or it may be operated automatically in response to a switch which is itself operated by the movement of the bucket or associated parts when a predetermined quantity of material has been deposited within the bucket and the device may be used in connection with a hoisting mechanism to load a skip which may operate vertically or in an inclined position. Another object is to provide means for automatically permitting an approximate volume, regardless of weight, to pass into a bucket. Another object is to provide automatic means for stopping the flow of material into the bucket and automatically controlling the start of its raising movement after the material has been delivered into it. Another object is to combine with such automatic weighing device means for closing the gate and starting the bucket upward when the proper weight of material has been received by the bucket.

Another object is to provide such automatic mechanism which will deliver an approximate weighed quantity of material, close the gate, start the bucket and continue to operate as long as there is material in the hopper. Other objects will appear from time to time in the course of the specification and claims.

The invention is illustrated more or less diagrammatically in the accompanying drawings wherein:

Figure 1 is a section through a loading mechanism with parts in section and parts broken away, showing the loader and bucket generally in side elevation with the bucket being lowered to the loading position;

Figure 2 is a similar view showing the bucket and parts in loading position where the material is weighed or measured;

Figure 3 is generally similar to Figures 1 and 2, showing the bucket after a predetermined weight of material has been received in it and after the gate has been closed;

Figure 4 is a vertical cross section taken on line 4—4 of Figure 2;

Figure 5 shows a modified form, employing the gate only, and with the chute omitted;

Figure 6 is a further modification without chute or gate, where the quantity of material delivered to the bucket is manually controlled.

Like parts are designated by like symbols throughout the specification and drawings.

A is a foundation with walls A¹ forming an enclosure or space A² within which the lower portion of the track and the loading mechanism is positioned. A³ is a hopper which is provided with an opening A⁴ in its bottom through which material may be delivered by the loading mechanism to the bucket.

B is a chute fixed in the door-way or opening A⁴ and is provided with a relatively long, extended bottom B¹ and a relatively short top or upper portion B² and side walls B³.

A swinging chute formed, in one form, generally of side walls C and a bottom C¹ is pivoted on a shaft C² and is supported from the fixed chute above mentioned.

It is provided on either side with contact members C³ which are in effect laterally extending flanges adapted to contact a portion of the bucket in the manner described below. Extending rearwardly from the movable chute are a pair of arms C⁴ C⁴ which are joined by a shaft C⁵ upon which are positioned counter weights C⁶. The chute C may be provided with a closed end C⁷ or with baffles C⁸ as shown in Figure 3, or with both of them. A swinging gate made up of side members D, D and a curved bottom member or plate D¹ is also supported from the fixed chute and adapted to move about the pivotal point C². The bottom plate D¹ terminates in an angularly disposed lip or flange D² which is adapted to engage the bottom plate C¹ of

65

the movable chute, as indicated particularly in Figures 2 and 3. At their rear the side plates D, D, are joined by a shaft D³ upon which are positioned counter weights D⁴.

5 The gate and movable chute are connected for co-operation by means of a pair of generally V-shaped pawl latches E, E. These latches are separately pivoted on the arms C⁴ as at E¹, E¹. At their lower ends each of 10 the pawls E is provided with a notch E² which in certain positions is adapted to engage a pin E³ on the side plates D of the gate. E⁴, E⁴ are spring shock absorbers pivotally mounted on the fixed chute as at E⁵ and engaging at their opposite ends a member E⁶ on the gate and adapted to serve as a shock absorber to cushion the closing movement of the gate. It will be noticed that when the gate is in the open position, as shown in Figure 2, the shock absorber is in the expanded position, and that the compression spring E⁷ is expanded, while when the gate is in the closed position as shown in Figures 1 and 3, the shock absorber is in the elongated position and in this position the compression spring E⁷ has been compressed. It is this spring, therefore, which serves as the cushioning element.

F is a track supporting structure. It is 30 fixed generally with relation to the foundation hopper and associated parts and contacts the foundation at F¹. At a point separated from its lower end F¹ it carries a fixed track section F². As shown, the track is 35 double. It could, however, be of any suitable shape. Hinged at F³ to the lower end of the track section F² is a movable section of track F⁴. Pivotally supported as at F⁵ on the supporting member F is a pair of levers F⁶, F⁶. 40 These levers carry at their outer ends counter weights F⁷, F⁷. At their opposite ends the levers F⁶ are slotted as at F⁸ to embrace pins F⁹ which are fixed in the swinging or movable track section F⁴. 45 G, G are trip rods provided with adjusting means G¹, G¹. These rods are attached, one on each side of the movable track section at the pins F⁹, at their lower ends and at their upper ends they are movably attached to levers G², G² which are themselves mounted on the shaft C² which forms the pivot point for movement of the gate and the movable chute. G³, G³ are cams fixed with relation to the levers G² and adapted to be moved by them 50 to operate the pawl latch E, E.

H is an electric switch mounted on the bottom of the fixed chute and provided with a handle or lever H¹. H² is a switch operating part mounted on the swinging gate and adapted to move with it. This part is adapted to contact and operate the switch lever H¹ in the manner described below.

I is a bucket, it is provided with pairs of rollers I¹, I¹. Pivotally attached to it are bail members I², I² which may be joined by

a shaft I³ and carry rollers I⁴. I⁵ is a hoisting cable of which there may be one or more. I⁶, I⁶ are brackets mounted preferably on either side, at the top of the front plate of the bucket and carrying rollers I⁷, I⁷ adapted to contact the flanges C³ of the swinging chute.

It will be realized that while I have shown and described an operative device, many changes may be made in the size, shape, relation, proportion and distribution of parts without departing materially from the spirit of my invention, and I wish, therefore, that this description and showing be considered as in a large measure diagrammatic. The bucket may also be arranged for loading and weighing and measuring in a vertical as well as in an inclined position.

The modified form shown in Figure 5 is generally similar to the form shown in Figures 1 and 2 except that the chute is omitted. The construction of the form shown in Figure 5 is substantially the same as that of Figure 2. The gate and other parts are the same. Since the chute is omitted, the latch E is pivotally supported not from the chute but from members E⁶ mounted on the fixed chute B. The track, counterweight and other associated features are the same as those shown in Figures 1 and 2.

In the form shown in Figure 6 a pit J is provided with foundations and walls J¹, J¹. Tracks J², J² are joined to the floor of the pit and are adapted to carry a dumping truck J³ which has a dumping body J⁴ tiltably mounted on it. J⁵ is a fixed hopper having an inclined bottom J⁶ and an open discharging side J⁷. The track J⁸ extends into the pit and is supported from a member J⁹ which is itself supported from the foundation J¹.

A second track L extends into the pit and is generally parallel with the track J⁸. It is provided with a movable portion L¹ which is attached by a hinge or other suitable means as at L² to the track L. L³ is a lever pivotally supported from the track J⁸ at L⁴ and connected at one end to the movable track section L¹. This counter weight through the lever is adapted to hold the track section L¹ upward so that it forms a continuation of the track L. The arrangement of the counter weight is such that when sufficient weight of material falls within the bucket, the counter weight is raised and the track section tilted or swung into the position shown in Figure 6.

M is a bucket having rollers M¹ M¹, one pair of which run on the track J⁸ and the others on the track L L¹. M² is a bail pivotally mounted at M³ on the bucket M carrying at its upper end one or more rollers M⁴ M⁴ which engage the tracks L L¹. M⁵ is a hoisting cable fastened to the bucket bail and adapted to raise, lower and control the position of the bucket.

N is a switch having a contact arm N¹ so situated that it is contacted by the pivoted track portion L¹ when it swings into the position shown in Figure 6. N² N² are wires in circuit with the control equipment governing the drum about which the cable is wound and unwound for hoisting, emptying, and lowering the bucket for reloading.

O is a delayed action switch. O¹ O¹ are wires leading to it. The function of the delayed action switch is to delay the effect of the action of the switch N. Thus when a weight of material sufficient to cause the track to swing, permitting the bucket to move, has fallen within the bucket, the track L will swing into the position shown in Figure 6, and the switch N will be operated, but this action will be somewhat delayed by the delayed action switch so that the hoisting mechanism which is in connection both with the limit switch and delayed action switch will not be set in motion at once, in order to give sufficient time for all of the material in the car to discharge into the bucket. Thus an appreciable delay is provided after the activating of the switch N before the hoisting mechanism is set in operation to raise the bucket.

The use and operation of this invention are as follows:

The mechanism shown may be made to operate in several different manners. Complete automatic operation is possible, operation which is manual in its control is possible and operation which is partially manual and partially automatic is possible.

I. Assuming the parts are in the position indicated in Figure 1, the gate is closed and the chute is in the upper position and the bucket is not in contact with either of these loader parts. The bucket is being lowered to the loading position and the rollers I⁷ contact the flanges C³ and move the swinging chute downward. The chute is joined to the gate by means of the latches E and their engagement with the pins E³ on the gate. Therefore the gate and chute being in engagement with each other, move together under the influence of the downward movement of the bucket into the position indicated in Figure 2. In this position the tiltable track section is held in its normal up position by the counter weight F⁷. If there is material in the track hopper it is now discharging or flowing into the bucket. When a sufficient weight of material has been received in the bucket, the bucket and the material will overbalance the counter weights which hold the tilting section of the tracks in the up position, and when sufficient weight has been received into the bucket, the tracks tilt into the position shown in Figure 3. The trip rods G then operate the cams G³ until they have swung the latches E upward. Thus the hooks E² have moved out of contact with the pins E³

and the gate is no longer held in the downward or open position by the chute, as in Figure 2. It is then free to move under the influence of the counter weights D⁴ into the closed position shown in Figure 3, thus cutting off further flow of material into the bucket. When the gate moves into the closed position, it operates the switch H, which is in circuit with the electrical motor control equipment for starting the hoisting operation. When the bucket is moved upwardly along the track out of the pit, its upward movement may or may not co-operate with the influence of the counter weights C⁶ to move the swinging chute from the position of Figures 2 and 3 back to the closed or upper position shown in Figure 1 and when the parts have reached this position the latches E again engage through the hooks E² the pins E³ and the swinging chute and gate are thus again locked together. The hoisting movement of the bucket continues until it reaches the dumping point, where it is stopped and the bucket is finally discharged, and after discharged, is again lowered into the pit for further loading. The electric wiring between the motor and the switch H is provided with the necessary control apparatus to automatically take care of the bucket's excursion after the switch H has been closed. As the electric control apparatus beyond the switch H constitutes no part of this invention and is well known to those familiar with skip hoists, it is not shown or described.

As the gate is returned to the closed position as indicated in Figure 3, and as the bucket is raised, the chute is free to move again to the upper or closed position indicated in Figure 1. As it does this the cam E is of course carried with it and swinging about its pivotal point E¹ its hook portion E² again engages the member E³ on the gate, and again the parts are in the position shown in Figure 1 in which the gate and chute are fastened together. Therefore, when the bucket is again lowered it will engage the chute and move it and the gate together into the loading position shown in Figure 2. The arrangement is such that the bucket can be operated either empty or with less than a full load by means of a push button or other manual control so that the bucket hoisting controls switch H may be manually operated or its circuit closed. This may of course be done without any automatic hoisting control and it may be done in combination with the automatic controlling means, by weight or by volume. This manual control may, of course, be accomplished without any automatic hoisting control and it may be done in combination with the automatic controlling means, and it may be done when the bucket is automatically loaded and controlled by weight or when it is automatically loaded

and controlled with not to exceed a given volume of material.

II. Another way in which the mechanism may be operated is as follows: This method differs generally from that just described above in the fact that the gate and chute, although arranged for relative movement, are locked together and operated in unison for delivering into the receptacle an amount not exceeding a given volume. In this form of operation the winding drum is automatically controlled and operated on a fixed, timed cycle, or may be operated manually by a push button. The weight operating feature above described in connection with the first method is cut out and is inoperative. This is made possible by having the electric switch H in the electric circuit with the motor driving the winding machine so that it may be cut out or cut in as desired. Therefore, the electric switch may be cut out and the movement of the gate, chute or any of the associated parts will not be effective to start or control the hoisting engine.

25 The tilting track may or may not be blocked by the part K of Fig. 1, so that it cannot swing down to unlatch the gate from the chute. Thus the gate and the chute are held together in all positions and the switch operation above described in connection with the first method cannot take place.

Where the weight operating feature is cut out the hoisting engine is normally started by a traveling cam limit switch. This switch may be of any suitable type and is well known in the art and is not shown or described. In general it operates to control the hoisting engine so that the bucket is moved to its various positions along the track and is stopped at predetermined points for predetermined time intervals. This method of operation differs generally from that first described above by the fact that the weight of the bucket and material do not serve to control the stopping and starting of the hoisting engine and by the further fact that the chute and gate operate together as a unit both in opening and closing and do not have relative movement.

50 In this mode of operation if the bucket is handling a material of which the weight of a volume sufficient to fill the bucket in combination with the weight of the bucket itself would not be sufficient to tilt the rails into the position shown in Figure 3, the gate and the chute will remain locked together and if there is material in the track hopper it will, with the parts in the position shown in Figure 2, discharge into the bucket and the material will fill the bucket and dam up in the chute against the end C⁷ and the baffles C⁸.

60 After the traveling cam limit switch driven from the winding engine provides sufficient time for the bucket to fill, the hoisting operation will automatically take place and any

material remaining in the chute will either fall into the bucket or remain in the chute, when the latter is moved to its raised position. As the bucket moves upward the gate and chute, since they are locked together, move upward together and the gate thus cuts the flow of material from the hopper. If the bucket is handling a material of which the weight of a volume sufficient to fill the bucket in combination with the weight of the bucket is sufficient to tilt the rails into the position shown in Figure 3, it then becomes necessary to provide positive mechanical means to prevent the rails from tilting and thus of course to prevent the unlatching of the gate from the chute before the bucket becomes completely filled. In this mode of operation, whether the track be blocked against tilting, or the switch H be cut out, the hoisting operation is as above described and is controlled by the traveling cam limit switch and in all positions the gate and chute remain latched together and held against relative movement.

III. It is desirable at times to have the skip controlled and operated on a definite time cycle and not the starting of the hoisting operation controlled by the weight of the skip and the material in it, as set forth under method I. For this operating condition assume the parts in position shown under Fig. 1 and skip is lowered to loading position Fig. 2, allowing material to discharge into the skip. During the time a definite predetermined weight of material has been discharged with in the skip, the skip or its associated parts have been moved into position Fig. 3 by the weight of the skip and material in it and the gate has closed but the gate does not move or actuate switch H as it does for operation method I. The traveling cam limit switch is set to allow enough time for material to discharge from stationary hopper to properly load the skip before it automatically starts the hoisting and other operations. The bucket gate and chute are controlled as described under method II except the chute need not be of the damming type and the gate moves relative to the chute when the gate moves from discharging to closed position.

IV. As shown in Figure 5 the mechanism is generally similar to that shown in the first four figures but the extended chute C is omitted. The operation of the form shown in Figure 5 therefore is as follows: As shown in that figure the bucket has been lowered to the loading position. The gate is open and if there is material in the hopper it is discharging into the bucket. When sufficient material has passed into the bucket so that the weight of the bucket and the material is sufficient, the tilting track section F⁴ swings downward, pulls the rod G, swings the cam G² G³ about the pivot C² and unlatches the cam E from the pins E³ on the gate, and

permits the gate to close under the influence of the counter weights D, shutting off the flow of material from the hopper. The gate in closing actuates the switch H and thus completing the electric circuit controlling the hoisting, emptying, lowering and stopping operations of the hoisting machine which actuates the bucket. The bucket is raised, stopped, dumped and returned automatically to the position for reloading.

This same mechanism could be operated without the automatic track swinging feature provided by the use of the switch H. This switch might be cut out in the manner described in connection with No. II and No. III above, and the movements of the bucket could be automatically controlled as its hoisting, emptying, discharging and loading operations on a predetermined cycle by means of a traveling cam limit switch driven from the winding machine. Of course, several types of controls actuated by the bucket or its associated parts might be used with the general construction shown in Figure 5 where the chute is omitted. Generally, therefore, the structure shown in Figure 5 may be operated on a completely automatic cycle controlled by the switch H or it may be operated without this switch and in that case the closing of the gate does not start the winding machine control equipment. In this operation the switch shown in Figures 1, 2 and 3 would not be necessary.

V. A further modified form of mechanism is shown in Figure 6. This mechanism embodies an automatic control for the bucket which is operated by the weight of a bucket and the weight of the material delivered to it. In this form of the mechanism a delayed action switch is used and the form of mechanism shown in Figure 6, without any gate, the material may be delivered to the bucket, the fixed hopper J⁵, or in some connections the hopper J⁵ may be omitted, and the material is delivered directly from the car body J⁴ into the bucket. In either of these forms there is no gate. Without any gate and especially if a slow flowing material is being discharged into the bucket, means may have to be provided to allow sufficient time for all material which is discharged from the car J⁴ to reach the bucket. Where the car J⁴ is dumped directly into the bucket, a sufficient time must then be provided to permit the body of the car to be swung out of the way of the bucket into its normal position before starting to hoist the bucket. It is preferable to actuate the switch N as shown in Figure 6 before all the material from the car reaches the bucket, otherwise the weight of the material and the bucket might not be sufficient to operate the switch and the bucket M might not be hoisted, emptied and returned to the loading position ready to receive the next car of material in

sufficient time. Preferably the counterweight L⁵ is set to tilt the track M after a small part of the car's contents has reached the bucket in response to the added weight of a minimum predetermined weight of material. The delayed relay and the predetermined minimum weight for actuating the switch automatically takes care of various loading conditions so that the attendant has only to bring the car to the loading point, dump its contents into the bucket and remove it as the bucket hoisting, emptying, lowering, and stopping for reloading operations are all automatically taken care of. The delayed action is to permit complete discharge of slow flowing material and removal of the car before the bucket is hoisted.

The importance of the delayed action switch is obvious, not only for taking care of sluggish flowing material and removal of the car, but also to meet certain operating conditions that will occur when car or cars containing less than the predetermined minimum weight of material are emptied into the bucket.

The switch will not be actuated by a car or cars containing less than the predetermined weight of material but it will be actuated by a car or cars containing any weight of material in excess of the predetermined minimum weight required for tilting the rail.

The bucket preferably should have sufficient capacity to hold the contents of a full loaded car plus the volume of a car or cars containing insufficient weight (less than the predetermined minimum weight) of material required for tilting the track and actuating the switch.

Various methods of operating the equipment above outlined may be further varied by the use of manual switches, controls and the like, which may be located at suitable points along the equipment so that the operator may control and vary the method of operation.

Under some conditions, as set out above, it will be desirable not to have the weight operated feature. This weight operated feature can be cut out by the provision of the bell crank latch K which, by means of a connecting rod K¹ leading up to the operator's seat, may be rotated into and out of position above the counterweight F⁷ so as to lock it down and prevent its yielding with the load in the skip. When this is done, the gate will not be unlatched from the chute and the chute then will carry the gate with it when it rotates upwardly responsive to the movement of the skip. As an alternative form, I have shown damming bars across the top of the open mouth of the chute so as to permit the gate and chute to operate together and of course operation in this connection may be at the will of the operator either automatic, by means of the time relay

switch controlled by the winding machine, or controlled directly and manually, by the operator, as the case may be. This construction may be used, of course, wherever it is desirable for any reason to prevent the downward swinging of the track section F⁴.

I claim:

1. In combination in a hoist, a fixed receptacle and a movable receptacle, tracks adapted to carry said movable receptacle to a position suitable for receiving and removing material from said fixed receptacle, a portion of said track adapted for limited movement under the influence of the combined weight of the movable receptacle and its load, a movable chute and a movable gate adapted to control the discharge of material from the fixed receptacle and adapted to have relative movement, means for engaging them against relative movement, and means for freeing the gate to permit it to close, said means operative in response to lateral movement of the movable receptacle.
2. In combination in a hoist, a fixed receptacle and a movable receptacle, tracks adapted to carry said movable receptacle to a position suitable for receiving and removing material from said fixed receptacle, a portion of said track adapted for limited lateral movement under the influence of the combined weight of the movable receptacle and its load, a movable chute and a movable gate adapted to control the discharge of material from the fixed receptacle and adapted to have relative movement, means for engaging them against relative movement, and means for freeing the gate to permit it to close, said means operative in response to lateral movement of the movable receptacle.
3. In combination in a hoist, means for automatically and positively delivering an approximately predetermined weight of material into a container, said means comprising a hopper, a track, a receptacle adapted to move along said track to receive material from said hopper, means for moving the receptacle, a chute and a gate, relatively movable, and means for actuating the chute and the gate to cause the two to move in unison, the receptacle being provided with parts to move the chute and the gate into their discharge position, a portion of the track being movable in response to the weight of the receptacle and load, means operated by the movement of said movable track portion for disconnecting the chute and gate whereby when said track portion moves, the gate is free to return to its closed position.

4. In combination in a hoist, means for automatically and positively delivering an approximately predetermined weight of material into a container, said means comprising a hopper, a track, a receptacle adapted to move along said track to receive material from said hopper, means for moving the re-

ceptacle, a chute and a gate relatively movable, and means for actuating the chute and the gate to cause the two to move in unison, the gate adapted to move to its closed position, the receptacle being provided with parts to engage the chute to move it and the gate into the discharging position, a portion of the track being movable in response to the weight of the receptacle and load, means operated by the movement of said movable track portion for disconnecting the chute and gate whereby movement of said track portion permits the gate to return to its closed position.

5. In combination in a hoist, means for automatically and positively delivering an approximate predetermined weight of material into a container, said means comprising a hopper, a track, a receptacle adapted to move along said track to receive material from said hopper, means for moving the receptacle, a chute and a gate relatively movable, and means for actuating the chute and the gate to cause the two to move in unison, the chute and gate each being counter weighted and adapted, when free to move, to move to their closed position, the receptacle being provided with a part to engage the chute to move it and the gate into their discharge position, a portion of the track being movable in response to the weight of the receptacle and load, means operated by the movement of said movable track portion for disconnecting the chute and gate whereby movement of said track portion permits the gate to return to its closed position.

6. In combination in a hoist, means for automatically and positively delivering an approximate predetermined weight of material into a container, said means comprising a hopper, a track, a receptacle adapted to move along said track to receive material from said hopper, means for moving the receptacle, a chute and a gate relatively movable, and means pivoted on the chute for actuating the chute and the gate to cause the two to move in unison, the chute and the gate each being counter weighted, the receptacle being provided with parts to engage the chute to move it and the gate into the discharging position, a portion of the track being movable in response to the weight of the receptacle and load, means operated by the movement of said movable track portion for disconnecting the chute and gate whereby movement of said track portion permits the gate to return to its closed position.

7. In combination in a hoist, means for automatically and positively delivering an approximate predetermined weight of material into a container, said means comprising a hopper, a track, a receptacle adapted to move along said track to receive material from said hopper, means for moving the receptacle, a chute and a gate pivoted on the hopper and relatively movable, and means

- pivoted on the chute for actuating the chute and the gate to cause the two to move in unison, the chute and the gate each being counter weighted and adapted, when free to move, to move to their closed position, the receptacle being provided with parts to engage the chute to move it and the gate into their discharge position, a portion of the track being movable laterally in response to the weight of the receptacle and load, means operated by the movement of said movable track portion for disconnecting the chute and gate whereby movement of said track portion permits the gate to return to its closed position. 70
8. In combination in a hoist, a hopper, a bucket adapted to receive material from said hopper, material guiding and controlling means including a movable gate and a movable chute, the two adapted for independent movement, and means for joining them together, the gate provided with parts adapted to engage the chute in its upper position and to cause the chute and gate to move into their discharge position, and means responsive to the weight of the bucket and the material in it for causing additional movement adapted automatically to free the gate from attachment to the chute whereby the gate is permitted automatically to close, and a hoist controlling mechanism adapted to be operated automatically by the gate in its closing movement. 80
9. In combination in a hoist, a hopper, a bucket, means for starting, stopping, raising and lowering the bucket, means for discharging material from the hopper into the bucket, said means including a movable gate and a movable chute, one of them carrying an attaching means whereby the two may be joined together, the two adapted to move together under the influence of the moving bucket to the loading position and a cam and cam operating parts adapted to be moved by the weight of material in the bucket to actuate the gate and chute connecting means to disconnect the two and thereby to permit relative movement of the two. 85
10. In combination in a hoist, a hopper, a bucket, means for starting, stopping, raising and lowering the bucket, means for discharging material from the hopper into the bucket, said means including a movable gate and a movable chute, one of them carrying an attaching means whereby the two may be joined together, the two adapted to move together under the influence of the moving bucket to the loading position and cams and cam operating parts adapted to be moved by the weight of material in the bucket to operate upon the gate and chute connecting means to disconnect the two and thereby to permit relative movement of the two, said means including a movable track section, 90
